US0D1040679S

(12) **United States Design Patent** (10) Patent No.: **US D1,040,679 S**
(45) Date of Patent: ** Sep. 3, 2024

(54) **BRACELET**

(71) Applicant: **Zhongqiang Guo**, Taian (CN)
(72) Inventor: **Zhongqiang Guo**, Taian (CN)
(**) Term: **15 Years**
(21) Appl. No.: **29/944,525**
(22) Filed: **May 29, 2024**
(51) LOC (14) Cl. **11-01**
(52) U.S. Cl. **USPC D11/5; D11/28**
